UNITED STATES PATENT OFFICE.

ALBERT J. LOEPSINGER, OF PROVIDENCE, RHODE ISLAND, ASSIGNOR TO GENERAL FIRE EXTINGUISHER COMPANY, OF PROVIDENCE, RHODE ISLAND, A CORPORATION OF DELAWARE.

FIRE-PROTECTIVE DEVICE.

Application filed October 4, 1924. Serial No. 741,753.

This invention relates to improvements in fire protective devices. More particularly it relates to devices for protecting a wall, such as the outside wall of a building, from adjacent fire. It has already been proposed for such purposes to provide a row of sprinklers at the cornice which should discharge water in thin sheets spreading over and running down threatened walls; but to begin such protection with the proximity of danger requires so great an expenditure from the water supply as is likely to tax the reserve of water too severely. Hence such curtains have not been frequently installed; but no way has been known to provide satisfactorily for the desired protection, so far as I am aware.

It is an object of the present invention to provide for such protection with economy of water; to defer the expenditure of water until actual need arises, to permit the preparatory turning on of water, in the system, when the danger is imminent or may possibly arise, without actual discharge and yet without danger of freezing when standing ready, and to this end to set the nozzle, valve, and waiting water in a location not exposed to danger of freezing, but protected by the building, yet with the distribution occurring in sheet form spread over the exterior of the endangered part of the wall, as for example, over any window, and to select automatically, according to need, the parts which are to be protected.

To this end the invention employs a new type of automatic sprinkler and an arrangement thereof by which its valve and nozzle are set inside of the building, preferably with the nozzle retracted from the valve, with a discharge tube extending thence outward through the wall of the building, as, for example, through the upper frame of the window sash, and provided outside with a deflector which distributes the issuing jet in sheet form over the window or other portion of wall below it. The part which projects through the wall is a relatively large tube through which the jet from the nozzle passes out as a free jet through air, unconfin ed. It is subjected to exterior atmospheric conditions and provided with a transverse partition or door which is normally closed. Exterior heat from an adjacent fire may pass by conduction through the metal

of the deflector and tube to the strut of the 55 sprinkler, and may be augmented by such heat as passes through the closed window. The heat of each part of a wall becomes considerable before there is real danger of ignition, or of fracture of window glass from 60 the heat; and any such temperature sends heat in by conduction in sufficient quantity and temperature to cause an automatic heat responsive valve to open and the jet to issue from within the building, while the window 65 remains closed and before the glass is broken. This is aided and made certain in the present case by the heat gathering effect of the outside of the deflector. The said partition may be a light plate hinged across the inner 70 end of the tube, arranged to open outward and held closed by a spring so weak as to yield when the jet is projected outward. The said tube may be connected by a metallic frame with the sprinkler piping and nozzle 75 within the building, in the form of diametrically opposite bars which hold the parts rigidly together yet allow ample space for access to said strut and valve; and a plug 80 may be provided for access to the interior space behind the valve. In ordinary usage the pipes leading to the nozzles of a series of such sprinklers may stand empty of water; but on the occurrence of a fire in the neighborhood water may be admitted thereto 85 by the opening of a main valve by hand; whereupon all parts of the system are ready for the automatic starting of a water curtain in any section where it is needed, whenever it is needed, without the wastage which 90 occurs from the anticipatory starting of such over the whole wall according to methods hitherto employed.

The invention may be embodied in various forms, one of which is illustrated in the accompanying drawings. It is intended that the patent shall cover by suitable expression in the appended claims, whatever features of patentable novelty exist in the invention disclosed.

In the accompanying drawings:

Figure 1 is a medial longitudinal section through a single sprinkler, tube and deflector;

Figure 2 is a bottom view of the same, 105 with part in section;

Figure 3 is a transverse section through the tube on the line 3—3 of Figure 1; and

Figure 4 is a view on a smaller scale showing a fragment of a building with the apparatus installed.

Referring to the drawings 10 represents the wall of a building which is to be protected, 11 is an apartment therein with floor 12 and window 13. The apparatus of the invention is contained in the tube 14 a location for which is seen in Figure 4, while 10 the tube itself is seen on a larger scale in the other figures. This tube is adapted to be inserted from the outside through the wall of the building and may be of any suitable length according to the thickness 15 of the wall. As illustrated, it is arranged to pass merely through the sash of the window 13. The inner end of the tube screws upon and is supported by the fixture 15 which is a part of or contains an automatic 20 sprinkler, the other part 16, of which, as is common with sprinklers, screws into a system of water distribution piping 17. The sprinkler has a nozzle 18 of suitable type to project a jet of water. The valve 25 of the sprinkler, and the means for holding the valve closed until released by heat may be of any suitable type, the construction illustrated being made on the principle of one that is well known in the market in 30 which there is a flexible diaphragm 19 with a central hole for passage of the jet, and the valve is a body 20 seated in said hole and maintained seated by the spring pressure of the diaphragm outward against it, 35 and through it against the fusible strut 21 which in turn is supported on a bridge 22 consisting of a sharp edged bar which, although it is in the path of the jet, affords but little resistance to it owing to the keenness of its edge and curvature as seen at 22'. 40 The fixture 15 has two parallel ring portions *a*, *b*, separated at a little distance and connected by side bars *c* which constitute ties in opposing the pressure transmitted 45 through the strut. The provision of side opening between the ring portions *a*, *b*, permits the valve 20 and its strut 21 to fall out when released, thereby leaving a clear 50 way for the water to discharge as a jet 55 through casing 14. Passing thus in a jet, the water has no tendency to escape through these openings. Their presence however, while the sprinkler is ready and waiting to be called into action, permits free circulation of room atmosphere about the valve 20 and its strut 21, so that the warmth and intimate contact of this air with the outer face of the valve minimize the effect of cold from out of doors, which might 60 otherwise freeze the water at the valve. At its end next to the nozzle the ring *a* of this fitting compresses and holds the diaphragm 19. The ring *b* which is remote from the nozzle holds the delivery tube 14 which is 65 screwed upon it, and is closed by an out-

side flap 23 which hangs by gravity and could be held by a light spring if desired. This flap constitutes a door which ordinarily prevents circulation of air between the inside of the building through the tube 14. It is so light, however, that it is immediately opened by the jet when the jet issues from the nozzle 18 and does not substantially affect the strength of that jet.

The tip 14' of the tube 14 is bent downward outside of the building and deflects the jet through an angle approaching 180 degrees, so that it is thereby thrown backward upon the exterior of the window or adjacent part of the building. The deflector may have any desired shape, either to produce a spattering or a smooth film distribution of the water according to the desired result.

For inspection, and to aid in setting the parts, a plug 30 is placed removably in the side of the chamber between the nozzle 18 and the valve 20 of the sprinkler.

In operation, any heat which is transmitted from without, through the wall or 90 through the tube 14 to the heat responsive strut of the sprinkler causes that to yield in the ordinary manner, after which water issues from the nozzle 18 assuming that it has been previously turned on, when 95 danger becomes manifest; but it does not flow from any nozzles except those where the heat is enough to require it, nor begin to flow until the heat requires it, thus greatly conserving supply of water.

I claim as my invention:

1. A fire protective device for the exterior of a building comprising, in combination, a nozzle with deflector for its jet, adapted to be set with said nozzle inside of and said deflector outside of the building, arranged to return the jet toward and spread it over the outside of the building wall; and a heat responsive valve for the nozzle, the heat responsive element of which is arranged 105 within the building in position to receive heat through the wall from a fire outside.

2. A fire protective device for the exterior of a building comprising, in combination, a nozzle with deflector for its jet, adapted to be set with said nozzle inside of and said deflector outside of the building, there being between the nozzle and deflector an opening through a wall of the building and a passage through said opening for the said jet, said deflector being arranged to return the jet toward and spread it over the outside of the building wall; and a yielding closure for the passage between the nozzle and the deflector, adapted to be opened by 110 the jet.

3. A fire protective device for the exterior of a building comprising, in combination, a nozzle with deflector for its jet, adapted to be set with said nozzle inside of and said

deflector outside of the building, arranged to return the jet toward and spread it over the outside of the building wall; and a tube extending through the wall, receiving the jet from the nozzle, and surrounding and guiding it to the deflector.

4. A fire protective device comprising a supply pipe with nozzle, a valve therefor and heat responsive means controlling the valve, all completely within a building and arranged to discharge a jet through a wall thereof; a deflector outside the building adapted to spread the said jet over the outside of the wall; the whole being located in position to receive heat from a fire outside of the building and thereby to be opened and to distribute its jets over the outside of said wall.

5. A fire protective device for the exterior of a building, comprising in combination, a nozzle, a tube adapted to pass through the wall of a building and arranged in line for the jet from the nozzle to pass through the tube, a deflector at the outer end of the tube adapted to turn the jet toward the face of the wall and a self closing door within the tube, adapted to open outward, yielding with such slight pressure as to let the jet pass substantially unimpeded.

30 6. A fire protective device for a wall comprising, in combination, a nozzle on one side of the wall, a tube surrounding and permitting free passage of the jet therefrom, adapted to extend through the wall, and 35 a deflector for the jet on the other side of the wall arranged to return it to the wall; the said nozzle having a heat responsive valve adapted to close the nozzle, there being a permanent opening for the escape 40 of the valve from the course of the jet after the valve has yielded in response to heat.

7. A fire protective device for a wall comprising, in combination, a nozzle on one side of the wall, a tube surrounding and permitting free passage of the jet therefrom, adapted to extend through the wall, and 45 a deflector for the jet on the other side of the wall arranged to return it to the wall; there being a valve, normally held closed 50 by heat responsive means, arranged at a little distance from the nozzle in the line of its jet; the space between said nozzle and valve being fully enclosed for holding water and having a removable section of wall.

55 8. A fire protective device for a wall comprising, in combination a tube adapted to pass through the wall and having on one side of the wall a nozzle with a heat responsive valve and on the other side of the wall a deflector for the jet of the nozzle; there being a bridge across the interior 60 of the tube adapted to support a strut for holding the valve closed, and adapted to afford but little resistance to the jet when the strut is removed.

9. A fire protective device for a wall comprising, in combination, a tube of heat conducting material adapted to extend through the wall, having a nozzle with a heat responsive valve at one end and having at its other end a deflector for turning the jet from the nozzle back upon the wall; the said tube affording a course for heat from a fire on the deflector side of the wall to pass to the heat responsive valve.

75 10. A fire protective device for a wall comprising, in combination, a nozzle with a heat responsive valve and tube leading thence through the wall; and a deflector for the jet at the further end of the tube; said tube and deflector being made of heat conducting material and having a relatively large area thereof, as compared with the heat responsive area of the valve, exposed to heat from a fire on its side of the wall whereby a considerable quantity of heat is received and transmitted by the tube to the heat responsive valve.

85 11. A fire protective device for a wall having a passage through it comprising, in combination, a nozzle with a heat responsive valve, adapted to throw a jet through the passage; there being a chamber housing the thermal element of said valve, open to atmosphere on the side of the wall where the nozzle is closed to the ingress of water from the nozzle and there being a closure for said passage against inflow of air through the wall; the said valve, thermal element, and closure of the passage through the wall being removable by the jet of water upon the yielding of said member in response to heat.

95 12. A fire protective device for the exterior of a building comprising, in combination, a nozzle adapted to be set within the building, a valve and thermally responsive strut arranged within the building and open to atmospheric conditions therein, and a tube passing through the building wall; and 105 a deflector outside thereof for distribution of the jet upon the wall of the building; the whole combination being arranged in three sections comprising respectively the nozzle, the valve and strut holding member, and the tube and deflector member.

110 13. A fire protective device comprising the combination, with a nozzle adapted to pass a jet through the wall and a tube and deflector adapted to guide the jet through and to the face of the wall, of a housing intervening between the nozzle and the tube, screw threaded to the body having the nozzle, and containing a valve with a heat responsive strut and a tube closing door, said valve, strut and door being adapted to yield 115 to the jet when the strut yields to heat.

120 14. A fire protective device for the exterior of a building comprising a supply pipe, nozzle and heat responsive valve therefor within the building, and a deflector outside 125

the building; there being an opening through a wall of the building for the jet from the nozzle to reach the deflector, and the whole being so arranged, adapted and located that the heat from a fire outside can reach and release the said heat responsive valve within.

15. A fire protective device for the exterior of a building comprising, in combination with the wall of the building, a nozzle with deflector for its jet, set with said nozzle inside of and said deflector outside of the building, arranged to return the jet toward and spread it over the outside of the building wall.

16. A fire protective device for the exterior of a building comprising, in combination with the wall of the building, a nozzle

set inside of the wall; a straight tube extending through the wall in the direction of the jet from the nozzle and large enough to afford unimpeded passage for the jet; and a deflector outside of the wall, at the end of the tube arranged and adapted to turn the jet toward the other side of the wall.

17. A fire protective device for a wall comprising, in combination with the wall, a nozzle with deflector for its jet, set with said nozzle on one side of the wall and said deflector on the other side of the wall, arranged to return the jet toward and spread it over said other side of the wall.

Signed at Boston, Massachusetts, this first day of October, 1924.

ALBERT J. LOEPSINGER.
